UNITED STATES PATENT OFFICE.

PATRICK BARNARD ROONEY, OF NEW YORK, N. Y.

DESIGN FOR A CORNER-IRON FOR BED-FRAMES.

SPECIFICATION forming part of Design No. 33,866, dated January 8, 1901.

Application filed December 6, 1900. Serial No. 38,969. Term of patent 7 years.

To all whom it may concern.

Be it known that I, PATRICK BARNARD ROONEY, a citizen of the United States, residing at New York, in the county of New York and State of New York, have invented and produced a new and original Design for Corner-Irons for Bed-frames; and I do hereby declare the following to be a full, clear, and exact description of the same, reference being had to the accompanying drawings, forming a part thereof.

My invention relates to a new and original design for corner-irons for bed-frames, and its leading and material features will be fully understood from the following description and claim when taken in conjunction with the accompanying drawings, in which—

Figure 1 is a perspective view of a corner-iron, showing my new design. Fig. 2 is an inverted perspective view of the same.

In said drawings similar letters of reference designate corresponding parts in both views, referring to which—

A is a frame of rectangular form in cross-section. This frame has a lip B, formed by the extension of one of its walls beyond the others, and is provided at one side and in line with one of its walls with a lateral flange C

of rectangular shape. Said flange is connected to the lower edge of the frame by a web 30 D, which is disposed at right angles to the flange and is gradually increased in width from its outer to its inner end, at which latter point it corresponds in width to the frame A.

The lower edge of the front side of the 35 frame is cut upwardly in approximately semicircular form in cross-section and has a projection E of the same form in cross-section extending therefrom, while at the back of the lower edge of the frame a semicircular 40 pending lip F is provided.

G is a horizontal partition which is provided with an an aperture H and is located near the bottom of the frame A.

Having described my invention, what I 45 claim as new, and desire to secure by Letters Patent, is—

The design for a corner-iron for bed-frames, as herein shown and described.

In testimony whereof I affix my signature 50 in presence of two witnesses.

PATRICK BARNARD ROONEY.
